PORTABLE ELECTRIC LAMP

Leo Gudeman, New York, N. Y.

Application July 18, 1935, Serial No. 31,965

3 Claims. (Cl. 248—300)

My invention relates to improvements in electric portable lamps and has reference particularly to the construction of a wall lamp or sconce, which is capable of being readily attached and detached from the wall, and which lends itself to an almost endless number of designs appropriate to this type of lighting fixture.

Portable wall lamps have already been devised and used with an extension cord and plug for connection in the ordinary electric wall sockets and these lamps have found a wide market, because of the fact that one may avail oneself of the beauty and charm of side wall electric light fixtures without the necessity of inter-wall wiring installations and the expense therefor. The present type of fixture has the added attraction that it is portable and may be made available wherever there is a wall socket to receive the plug connection.

The object of the present invention is to improve upon the known types of portable wall fixtures by making a bracket of one piece of springy material, one arm of which is longer than the other so as to bring the bracket under tension when it is in attached position to hold it firmly against displacement and to aid in maintaining its proper upright position.

A further object of my invention is to provide a slotted aperture in the fixture which will enable the electric extension cord to take its proper position without requiring it to be threaded through a series of openings with the result that the plug may be attached to the cord before assembling the lamp bracket.

I accomplish these objects by means of the embodiments of my invention hereinafter described in the specification, set forth in the appended claims and illustratively exemplified in the accompanying drawing, in which

Figure 1 is a side elevational view of the portable wall lamp;

Figure 2 is a back view of the same; and

Figure 3 is a perspective view of a modified form of bracket.

Referring to the drawing and particularly to Figures 1 and 2, 10 denotes a side wall to which the wall bracket may be attached and 11 the push pin or tack which has been placed in the wall and forms a support for the bracket.

The bracket, designated 12, comprises a substantially V-shaped member bent from a single strip of springy material, preferably steel, one arm 13 being longer than the other arm 14 and both arms having their free ends curved into coils 15 following the same direction. In position

for use as a bracket the V-shaped member is disposed with one arm directly above the other, the shorter arm 14 being the uppermost and at right angles to the wall 10 while the longer arm 13 projects downwardly at an inclination towards the wall. The normal position of the longer arm 13 when not under tension, i. e., when free of the wall, is substantially that indicated in dotted lines in Figure 1, but when the free end of arm 14 is brought into contact with the wall, the arm 10 13 springs to the full line position and is held under tension and in frictional contact with the wall at its free end. The curved portion of the coil 15 of the upper and shorter arm 14 abutting the wall is provided with an orifice 16 to accommodate the passage of the head of the pin 11 therethrough and to allow the head to seat itself against the inner curved surface of the coil and to provide a more or less tension hold of the pin upon the bracket. The longer arm 13 is provided with an elongated slot 17 extending about the curve in the coil 15 abutting the wall, the slot 17 allowing the electric cord 18 to pass from the space between the arms 13 and 14 and to a point below the bracket without the necessity of threading it through any opening in the lower arm.

Any type of electric fixture may be mounted upon the upper arm 14, but for purposes of illustration I have shown a lamp comprising a ball bottom 19 set in a depression 20 in the mid-portion of the arm 14, lamp socket 21 mounted upon the ball 19, an incandescent bulb 22 in the socket and a shade 23 carried by the bulb. The socket 21 is of the type provided with a switch 30 and bottom 24. The ball bottom 19 is attached to the arm 14 by means of a screw connection 25, which allows the cord 18 to pass therethrough into the space between the arms 13 and 14, and which passes through an opening 26 in the arm to receive a nut 25 capable of being screwed over the connection and against the under-face of the arm to firmly hold the lamp in position. The free end of the extension cord 18 is provided with the usual plug in connection 28 mounted in the wall 10 adjacent the floor.

Referring now to Figure 3, the bracket in this embodiment comprises a straight wall portion 29 and an outwardly curved portion projecting from the wall in a curved line to form the longer arm 13^a, the shorter arm 14^a being constructed by turning the material at the outer end of arm 13^a upwardly and then backwardly again upon itself. The free end of the shorter arm 14^a is curved in a coil 30 having an orifice 31 to accommodate 55

the pin 11. The outer end of the shorter arm 14^a is provided with an orifice 32 to receive a lamp fixture 33, the cord 18 projecting downwardly over the face of the longer arm 13^a and 5 being guided to a point below the bracket in an upright slot 34 in the straight wall portion 29. The lower end of the longer arm 13^a is provided with a projecting arm 35 disposed at right angles to the portion 29 and arranged directly beneath 10 the other arms 13^a and 14^a. Mounted on the top of this arm 35 is a dish or any other receptacle 36 for a flower pot, vase or the like.

To install the present bracket, the pin 11 is placed in the wall 10 at the desired location and 15 the opening 16—31 in the shorter arm 14, 14^a is placed over the head of the pin which is then allowed to project through the opening. The bracket moves down slightly until the top wall 20 of the opening 16—31 rests upon the stem of the pin and the head engages the material about the opening. When the upper arm 14, 14^a is set the latter will be at right angles to the wall 10 and the longer arm 13, 13^a will spring outwardly and 25 downwardly until it is in contact with the wall to hold the bracket in position.

Having now described my invention and the manner in which the same is operated, what I claim and desire to secure by Letters Patent is:

1. In combination, a bracket of springy material having a pair of arms, one thereof being 5 shorter than the other and adapted to support a lamp, the free end of the longer arm being slotted to accommodate an electric cord from the lamp, and means to attach the free end of the shorter arm to a supporting surface, while 10 the longer arm springs away from the shorter arm to bring its free end into frictional contact with the supporting surface.

2. A bracket, as claimed in claim 1, in which the free ends of the arms are curved into downwardly directed coils, the openings being disposed in the portions of the coils engaging the supporting surface.

3. The combination claimed in claim 1, which comprises a supporting arm attached to the free 20 end of the said longer arm, said supporting arm being inclined with respect to the supporting surface and adapted to support a weight in order to produce stable suspension of the bracket.

LEO GUDEMAN. 25
